UNITED STATES PATENT OFFICE.

EDWARD H. MCPHERSON, OF JEFFERSONVILLE, INDIANA.

GAME APPARATUS.

Application filed December 19, 1922. Serial No. 607,875.

To all whom it may concern:

Be it known that I, EDWARD H. MCPHERSON, a citizen of the United States, residing at Jeffersonville, in the county of Clark 5 and State of Indiana, have invented certain new and useful Improvements in Game Apparatus, of which the following is a specification.

This invention relates to game apparatus; 10 and has as its general object to provide an apparatus which may be employed in playing a game substantially in accordance with the rules and regulations governing the playing of the game of base ball.

15 Another object of the invention is to provide game apparatus so constructed that the players using the same will be influenced to exercise a degree of skill in making their plays thus enhancing the attractiveness of the apparatus.

Another object of the invention is to provide a game apparatus for the purpose stated which may be employed with the greatest convenience and without occasion 25 for repeatedly rearranging the parts thereof in the course of play.

In the accompanying drawings:

Figure 1 is a front elevation of the apparatus embodying the invention; 30 Figure 2 is a vertical front to rear sectional view on the line 2-2 of Figure 1;

Figure 3 is a detail view in rear elevation of a portion of the apparatus;

Figure 4 is a similar view but illustrating 35 the indicator disc in a reversed position;

Figure 5 is a detail vertical sectional view on the line 5-5 of Figure 4;

Figure 6 is a view looking at the upper side of the suspension means for the indicator discs;

Figure 7 is a side elevation of the said means.

The apparatus embodying the invention includes a board which is indicated in general by the numeral 1 and which may be of any desired dimensions and is preferably supported by legs 2 and by an easel frame, indicated in general by the numeral 3, and comprising spaced side members or standards 4 hingedly connected at their upper ends as at 5 to the rear side of the board 1 at the top thereof and at the opposite vertical edges of the board. The standards 4 of the easel frame are braced by cross rods 6 and 7, and the rod 6 serves an additional purpose which will presently be

pointed out. By reference to Figure 2 of the drawings it will be observed that when the apparatus is set up for use, the board 1 will be supported in a slightly rearwardly inclined position.

At or close to its top the board 1 has painted or otherwise displayed upon its face a ruled area 8 for the keeping of the score, and below this portion and near its bottom bears the representation of a base ball diamond, as indicated by the numeral 9. Within the diamond representation, the board is formed with a number of openings 10, 11, 12 and 13, preferably located within the four corners of the diamond, and with an opening 14 which is located centrally of the diamond. Above the diamond and in a row extending transversely beneath the score board area 8, the board 1 is provided with a series of openings 15, 16 and 17. At or close to its top the board 1 has painted or otherwise displayed upon its face a ruled area 8 for the keeping of the score, and below this portion and near its bottom bears the representation of a base ball diamond, as indicated by the numeral 9. Within the diamond representation, the board is formed with a number of openings 10, 11, 12 and 13, preferably located within the four corners of the diamond, and with an opening 14 which is located centrally of the diamond. Above the diamond and in a row extending transversely beneath the score board area 8, the board 1 is provided with a series of openings 15, 16 and 17. Above the diamond and below the row of openings 15, 16 and 17, the board is provided with openings 18, 19, 20 and 21, and similar openings 22 and 23 are provided 75 exteriorly of the lower portion of the diamond and at opposite sides of the opening 10. Openings 24 and 25 are provided within the bounds of the diamond respectively between the openings 11 and 12 80 and the openings 12 and 13, and other openings 26 and 27 are also provided within the bounds of said diamond and respectively between the openings 10 and 11 and 10 and 13. The openings 10, 11, 12, 13 85 and 14, within the diamond, represent the positions of the players in the field, and the openings 15, 16 and 17 represent, respectively, left field, center field, and right field positions.

95 The game is played with an inflated rubber ball (not shown), which is preferably not thrown directly at the board but is bounced from a point in advance of the board and in the direction thereof so that it may pass through any one of the various openings in the said board.

Plays which result by projecting the ball through one or another of the openings 10, 11, 12, 13, 15, 16 and 17 are indicated by indicator discs which are suspended in juxtaposition to the openings in a manner which will now be described. In the drawings the said discs are indicated in general by the numeral 28 and each comprises a circular 105 plate of wood or metal of a diameter somewhat less than that of the opening in juxtaposition to the opening 10, 11, 12, 13, 15, 16 and 17.

position to which it is to be suspended. The disc is provided at the upper side of its periphery with an eye 29 with which is permanently and pivotally engaged a loop or eye 30 formed at the lower end of a suspension element 31 which may be made from a suitable length of wire or small rod material. At its upper end the suspension element 31 is bent to form an eye 32 which is open near 10 its juncture with the said element, as at 33, and has its end, at its open side, turned back upon itself, as at 34, thereby adapting the eye to be readily hooked over an attaching means which is provided upon the rear side 15 of the board 1 above the respective opening in the board. The attaching member referred to above is indicated in general by the numeral 35 and the same comprises an attaching plate 36 secured to the rear face of 20 the board 1 at such distance above the respective opening in the board that when the suspension element 31 is engaged therewith in a manner to suspend the respective disc 28, the disc will occupy a position approxi- 25 mately concentric to the said opening but rearwardly thereof and in a vertical plane as shown most clearly in Figure 5, although the board 1 is, as previously stated, supported in a slightly inclined position. Upon the at- 30 taching plate 36 there is secured a substantially V-shaped staple 37, the side members 38 of which are inclined upwardly and rearwardly to their point of juncture. By refer- 35 ence to Figures 3 and 4 of the drawings it will be observed that when the eye 32 of the suspension element 31 is engaged with the staple, it will seat at the lower end of one or the other of the side members 38 of the said staple and, of course, when it seats at 40 the lower end of one of said side members, one face of the respective disc 28 will be displayed through the opening, and when it seats at the lower end of the other side member the other face of the disc will be dis- 45 played through the opening, the two faces bearing different legends. For example, one face of each disc will bear the legend "Out." The opposite faces of the discs which are associated with the openings 10, 11, 12, 13 50 and 14 will respectively bear legends reading as follows: "Bunt single," "3rd B single hit," "2nd B single hit," "1st B single hit," and "Base on balls." The discs which are associated with the openings 15, 16 and 17 will 55 respectively bear upon their said other faces legends as follows: "L F 3 base hit," "C F home run," and, "R F 2 base hit." The openings 18, 19, 20 and 21 are unob- 60 structed and at the upper side of these openings there are arranged legends reading re- 65 spectively as follows: "Double play batter out," "Triple play batter out," "Triple play batter out," "Double play batter out." The openings 22 and 23 are likewise unobstructed, and are indicated at their upper sides by

legends reading "Foul play." The openings 24 and 25 are likewise unobstructed and each is designated by the legend "Grounder out." The openings 26 and 27 are likewise unobstructed and are designated each by a legend reading "Pop-up out." 70

As previously stated, each indicator disc is provided upon one face with the legend "Out" and upon its other face with a legend indicating a successful play, and it will be 75 evident that the playing ball, in being projected through any one of the openings with which these discs are associated, will strike the respective disc and probably at one side of the center thereof, in which event the disc, at the time it is swung rearwardly, will also, in all probability, rotate in one direction or the other due to the looseness of the connection of the eye 32 with the staple 37. 80

In thus rotating, the eye will ride upwardly along one of the side members 38 of the staple and downwardly along the other side member and if the impetus given the disc is sufficiently great, the eye may pass back and forth over these side portions of the staple 85

several times, the position of the disc being reversed each time, but finally it will come to rest at the lower end of one or the other of said side portions, and at such time the disc will be suspended in position to display 90

one or the other of its faces through the opening with which it is associated, thus indicating the success of the play. In the instance of the openings which are unobstructed, or, in other words, with which the indicator discs are not associated, the plays made 95

are indicated by the legends associated with the respective openings through which the ball is projected. 100

In order that the ball after being projected through any one of the openings may be returned to the player's station, and thus conveniently recovered by him for a succeeding play, a back stop and ball delivering means is provided in rear of the board 105

and is indicated in general by the numeral 39 and comprises a sheet 40 of cloth or other suitable material which is secured at one end edge as at 41 to the rear side of the board preferably at the upper edge there- 110

of and is led downwardly and over a stretcher 42, about the cross rod 6, and then connected at its lower edge to a cross rod 43 which extends between the supporting legs 2 for the board. The stretch of the 115

cloth between the stretcher 42 and cross rod 6 is located in a plane substantially parallel to the plane occupied by the board 1, but the stretch of the cloth between the said cross rod 6 and the cross rod 43 is inclined 120

downwardly and forwardly so that after the ball has been projected through one or another of the openings in the board it will eventually fall upon the inclined last-mentioned stretch of the cloth and roll there- 125

from onto the ground or floor surface and toward the player.

The stretcher 42 is preferably formed from rod material and comprises side members 44 and a connecting member 45, the latter member engaging against the sheet 40 and the side members 44 being pivotally mounted between their ends as at 46 upon the uprights 4 of the easel frame 3. The 10 ends of the side members 44 of the stretcher which are next adjacent the board 1 are provided with hooks 47 which are engageable in eyes 48 upon the rear side of the board, and it will be evident that after the 15 board 1 has been set up and the easel frame has been adjusted the cloth 40 may be tensioned by swinging the stretcher 42 about its pivot 46 so as to cause its connecting portion 45 to ride rearwardly against the cloth 20 and its hooked ends 47 to engage in the eyes 48.

It will be evident that the game apparatus embodying the invention is adapted to be collapsed when not in use so that it may 25 be stored away or shipped in a compact form. It will also be understood that considerable skill may be developed in the use of the apparatus.

Having thus described the invention, what 30 is claimed as new is:

1. Game apparatus comprising an upright board having an opening therein for the passage of an impelled game piece, and an indicator freely suspended in juxtaposition to the opening at the rear of the board whereby either face may be presented to the opening and bearing different play indications upon its opposite faces.

2. Game apparatus comprising an upright 40 board having an opening therein for the passage of an impelled game piece, and an indicator freely suspended for swinging movement to and from the board and rotative movement about its vertical axis in 45 juxtaposition to the opening at the rear side of the board whereby it may present either face to the opening and bearing different play indications upon its opposite faces.

3. Game apparatus comprising an upright 50 board having an opening therein for the passage of an impelled game piece, a member upon the rear side of the board above the opening having upwardly inclined converging side portions, a suspension element having an eye loosely engaging said member and movable along the same to assume a position upon either of said side portions

whereby it may be reversed, and an indicator disc supported at the lower end of 60 the said suspension element and in juxtaposition to the opening and having different play indications upon its opposite sides.

4. Game apparatus comprising an upright 65 board having an opening therein for the passage of an impelled game piece, a member upon the rear side of the board above the opening having upwardly inclined converging side portions, a suspension element 70 having an eye loosely engaging said member and movable along the same to assume a position upon either of said side portions whereby it may be reversed, and an indicator disc pivotally supported at the lower 75 end of the said suspension element and in juxtaposition to the opening and having different play indications upon its opposite sides.

5. Game apparatus comprising an upright 80 board having an opening therein for the passage of an impelled ball, a frame supporting the board in upright position and including a cross member, the board being provided with supporting leg portions, a 85 cross member extending between the said leg portions, and a sheet of flexible material connected to the upper portion of the back of the board and stretched over the cross member of the frame and connected at its 90 lower portion to the last-mentioned cross member whereby to provide a portion facing the back of the board and a lower portion inclined downwardly and forwardly 95 therefrom.

6. Game apparatus comprising an upright board having an opening therein for the passage of an impelled ball, a frame supporting the board in upright position and including a cross member, the board being 100 provided with supporting leg portions, a cross member extending between the said leg portions, a sheet of flexible material connected to the upper portion of the back of the board and stretched over the cross member of the frame and connected at its 105 lower portion to the last-mentioned cross member whereby to provide a portion facing the back of the board and a lower portion inclined downwardly and forwardly 110 therefrom, and a stretcher member mounted for swinging movement upon the said frame and movable into position to ride and bear rearwardly against the said sheet.

In testimony whereof I affix my signature.
EDWARD H. McPHERSON. [L.s.]
